UNITED STATES PATENT OFFICE

GEORGE H. GILMAN, OF BOSTON, MASSACHUSETTS

DRILLING MACHINE

Application filed September 2, 1920, Serial No. 407,773. Renewed March 28, 1929.

My invention relates to machines used in the forming of holes, and particularly, but not exclusively, to drilling machines for forming holes in rock and other earth formations.

My invention will be best understood from the following description when read in connection with the accompanying drawings of one specific embodiment of my invention submitted for illustrative purposes, while its scope will be more particularly pointed out in the appended claims.

In the drawings:

Figure 1 is a central longitudinal section through the submitted embodiment of my invention; and

Figs. 2, 3 and 4 respectively are sections on the lines 2—2, 3—3 and 4—4 of Fig. 1.

Referring to the drawings, I have shown a stoping drill in which is embodied means for feeding the drill steel to the work, percussive means for impacting the drill steel, and an independent rotation motor for rotating the drill steel. As the details of these instrumentalities, per se, do not form part of my present invention, the same will be described only with sufficient particularity to point out their application to the invention claimed.

The percussive means illustrated comprises a casing including a cylinder member 1 in which is reciprocably mounted a hammer piston 2. Forwardly of the cylinder the casing comprises a part 3, hereinafter termed the chuck casing, in which is rotatably mounted a chuck 4 provided with a polygonal bore for receiving the polygonal shank 5 of the drill steel.

As illustrated a motor and drive are provided for rotating the drill steel, this motor and drive preferably being mechanically reversible, that is to say, they are so constructed that if a force is applied to the drill steel tending to rotate it in either of opposite directions the motor and drive will be correspondingly rotated. To this end herein is provided a fluid pressure actuated spur gear rotary engine and a spur gear reduction gearing, the latter connecting the engine to the rotatably mounted chuck. The provision of mechanically reversible fluid pressure actuat-

ed means for rotating the drill steel relative to the casing among other things allows the casing to be rotated relative to the drill steel in either of opposite directions so as to clear obstructions presented to the casing while the hole is being drilled.

The chuck rotating engine in the present embodiment of my invention comprises the rotary piston 6 having the rotary abutments 7 and 8 arranged at opposite sides thereof, the piston being provided with piston vanes cooperating with the abutments and with gear teeth meshing with gear teeth on the abutments for driving the latter. The rotary piston 6 is mounted for rotation on the reduced diameter portion 9 of the cylinder for the hammer piston while the abutments are carried by shafts 10 and 11 which respectively carry at their forward ends the eccentrics 12 and 13.

Mounted on the eccentrics so as to be gyrated thereby is the yoke 14 provided with the internal spur gear portion 15 meshing with the external spur gear portion 16 of the chuck. The yoke and eccentrics herein form a reduction gearing which constitutes part of the drive between the motor and the drill steel.

Although my invention is applicable to handle supported and mounted drilling machines it is of particular advantage when applied to stopers. As illustrating one form of stoker I have shown, carried by the rear cylinder head 17, the stoker feed cylinder 48, which latter is provided with a piston 49 carrying the stoker piston rod 20. The stoker piston rod, as will be understood by those skilled in the art, has means for engaging the rock or suitable support in order that the drill steel may be fed to the work by motive fluid admitted to the feed cylinder.

As illustrating a control for the machine I have shown mounted in the cylinder head 17 a throttle valve 18 the latter provided with a central conduit 19 adapted to be placed in communication with the source of motive fluid. As will be understood by those skilled in the art, this valve is adapted to control ports and passages for admitting motive fluid into the feed cylinder, to feed the drill steel.

up to the work, and into the percussive cylinder for operating the piston. This valve, the details of which form no part of the present invention, may be the known form of turning plug used in stoping drills, as for example that shown in United States patent to Taylor, 898,702, granted September 15, 1908.

For reciprocating the hammer piston I herein have formed the cylinder with a bore 10 21 of relatively large diameter and a bore 22 of relatively small diameter, and have formed the piston with the large diameter portion 23 and relatively smaller diameter portion 24, the latter connected to the large diameter portion by a reduced diameter portion 25. The air admitted from the throttle valve 18 passes into the rearward end 26 of the small diameter portion of the cylinder, whence it finds its way through one or more 20 passages 27 to the groove 28 at the forward end of said portion, the rearward end of the cylinder and groove 28 thus constituting what are usually termed in the art "constant pressure chambers." Leading from the intermediate portion of the smaller diameter portion 25 of the cylinder to the forward end of the cylinder portion 23 of larger diameter is a passage 29. From the intermediate portion of the portion of larger diameter leads an 30 exhaust passage 30 connecting said portion with the atmosphere, and adapted to be covered and uncovered by the piston in its reciprocations to exhaust motive fluid from opposite sides of the piston.

35 When the piston is in the position shown by Fig. 1, the motive fluid is admitted from the constant pressure chamber 28 to the rearward end of the cylinder portion of larger diameter by means of the conduit formed by the reduced diameter portion 25 of the piston, and, as the forward end of the cylinder portion of larger diameter is connected to the atmosphere at this time, the piston moves forwardly and delivers the blow. When the 40 piston moves forwardly, the connection between the chamber 28 and the rearward end of the cylinder portion of larger diameter is interrupted, and at the forward end of the stroke the rearward end of the smaller diameter portion of the piston uncovers the rearward end of the passage 29 to admit fluid from the constant pressure space 26 through the said passage to the forward end of the cylinder, and, as at this time the rearward 45 end of the cylinder portion of larger diameter is open to the atmosphere through the port 30, the piston returns to the position 50 shown by Fig. 1.

For bodily rotating the machine I herein 60 have provided a rotation handle 31 carried by the rear cylinder head and pivoted at 44 to be turned to project at right angles to the machine. In order to permit this handle to rotate the steel I herein have provided 65 means for locking the steel against rotation,

and, although I may lock any part of the motor or drive to secure this result, I preferably lock the chuck to the chuck casing in order to take the strain off the gearing which would exist if the other arrangements were employed. To this end, I herein provide the chuck casing with a transversely formed boss 70 32 in which is slightly mounted a bolt having the parallel portions 34 and 35 and connecting portion 36. On the forward end of the portion 35 I have shown a detent 37 adapted to engage complementary recesses 38 formed in the exterior surface of the chuck. For operating the bolt I have illustrated the same as provided with a handle 39, and for holding the same in its locked and unlocked positions I may provide the recesses 40 adapted to be engaged by the spring-pressed pin 41. As will be obvious, when the bolt is in the position shown by Fig. 4, the chuck is prevented from rotating, and under such conditions the drill may be rotated by the handle 31. When the bolt is moved to disengage the chuck, the motor may rotate the drill if the cylinder is prevented from rotating by means 80 of the handle 31.

It will be understood that, although I have shown the lock as applied to an overhead stoping machine, where it is of particular advantage, it may also be advantageously applied to all forms of machines with which it may be desired to manually rotate the drill steel and whether or not the drive is reversible.

As shown in Fig. 2, the motor for rotating the drill is provided with inlet passages 42 and exhaust passages 43. The inlet passages 42 are both in constant communication with the continuous pressure space 26 of the drilling machine, one of these passages being shown in Fig. 1, the other passage, not shown, being similarly constructed. Both exhaust passages 43 are directed forwardly and open to the atmosphere through ports 44 formed in the shoulder 45, one exhaust passage being shown in Fig. 1 and the other being similarly constructed.

It will be noted that I have provided a drilling machine having extensible feeding means and percussive means for operating the tool, and have further provided manual means and a mechanically reversible power means for rotating the tool, and that when the steel is locked against rotation by the power means, the same may be rotated by the 115 manual means.

It will be understood that within the scope of the invention wide deviations may be made from the specific embodiment thereof herein described without departing from the spirit of the invention.

Claims:

1. A rock drilling machine having, in combination, a casing, an extensible feeding device operatively secured to said casing, said 130

feeding device having a rearwardly projecting member for engagement with a support for the machine, a chuck rotatably carried by said casing, said chuck formed for carrying a drill steel in such manner that said steel must rotate when said chuck is rotated, a hammer piston in said casing for operating said drill steel, a mechanically reversible fluid actuated motor connected by a mechanically reversible drive to said chuck, and releasable means operative to present said chuck from rotating relative to said casing whereby said steel may be rotated by manually rotating said casing.

2. A rock drilling machine having, in combination, a casing, an extensible feeding device operatively secured to said casing, said feeding device having a rearwardly projecting member for engagement with a support for the machine, a chuck rotatably carried by said casing, said chuck formed for carrying a drill steel in such manner that said steel must rotate when said chuck is rotated, a hammer piston in said casing for operating said drill steel, a motor and reduction gearing for rotating said chuck, and releasable means operative to lock said chuck directly to said casing whereby to prevent rotation of said chuck relative to said casing and permit said steel to be rotated by rotating said casing.

3. A hammer rock drilling machine having, in combination, a casing, a chuck rotatably mounted on said casing, said chuck formed for carrying a drill steel in such manner that when said chuck is rotated said steel must rotate with it, a mechanically reversible motor and reduction gearing for rotating said chuck, independently of the operation of the hammer and releasable means operative to prevent said chuck from rotating relative to said casing.

4. A hammer rock drilling machine having, in combination, a casing, a chuck rotatably mounted on said casing, said chuck formed for carrying a drill steel in such manner that when said chuck is rotated said steel must rotate with it, a mechanically reversible motor and reduction gearing for rotating said chuck, independently of the operation of the hammer and releasable means operative to lock said chuck directly to said casing.

5. A hammer rock drilling machine having, in combination, a casing, a chuck rotatably mounted on said casing, said chuck formed for carrying a drill steel in such manner that when said chuck is rotated said steel must rotate with it, a motor for rotating said chuck independently of the operation of the hammer, a mechanically reversible reduction gearing for operatively connecting said motor and chuck, and releasable means operative to lock said chuck directly to said casing.

6. A rock drilling machine having, in combination, a casing, a chuck rotatably mounted on said casing, said chuck formed for carrying a drill steel in such manner that when said chuck is rotated said steel must rotate with it, a fluid actuated motor for rotating said chuck, driving means between said motor and chuck, a fluid actuated hammer piston for imparting percussion to said drill steel, said motor and hammer piston carried by said casing, motive fluid control means for said motor and hammer piston effective to cause one to operate when the other operates, and releasable mechanical means operative to prevent rotation of said chuck by said motor when said hammer piston is operating.

7. A rock drilling machine having, in combination, a casing, a chuck rotatably mounted on said casing, said chuck formed for carrying a drill steel in such manner that when said chuck is rotated said steel must rotate with it, a fluid actuated motor for rotating said chuck, driving means between said motor and chuck, a fluid actuated hammer piston for imparting percussion to said drill steel, said motor and hammer piston carried by said casing, motive fluid control means for said motor and hammer piston effective to cause one to operate when the other operates, and releasable means operative to lock said chuck directly to said casing to prevent rotation of said chuck whereby when desired said hammer piston alone may operate.

8. A rock drilling machine having, in combination, a casing, a chuck rotatably mounted on said casing, said chuck formed for carrying a drill steel in such manner that when said chuck is rotated said steel must rotate with it, a fluid actuated motor for rotating said chuck, a fluid actuated impact motor for said steel comprising a hammer piston, means for supplying motive fluid to said impact motor and hence to the other motor whereby when said impact motor operates said other motor will be supplied with motive fluid for actuation thereof, independent exhaust and fluid distributing means for said motors whereby said impact motor may operate when said other motor is forcibly held from operating, and releasable mechanical means effective to prevent operation of said other motor whereby when desired said impact motor alone may operate.

9. A stoping machine having, in combination, a fluid actuated hammer drill comprising a casing rotatably carrying a chuck for the drilling tool, feeding means for said tool comprising a relatively rotatable feed cylinder and piston one of which is attached to said casing, a mechanically reversible fluid actuated motor and gearing means for rotating said chuck relative to said casing, and means operative at will to prevent rotation of said chuck relative to said casing.

10. A stoping machine having, in combination, a feed cylinder member and a cooperating feed piston member, a hammer drill having a casing member connected to one of said feed members, a substantially radially disposed rotation handle carried by one of said members, a chuck rotatably mounted on said casing member of said hammer drill, a mechanically reversible motor carried by said hammer drill for rotating said chuck, a mechanically reversible reduction gearing carried by said hammer drill for operatively connecting said motor to said chuck, and releasable means operative at will to prevent rotation of said chuck relative to said casing. 75
11. A stoping machine having, in combination, a feed cylinder member and a cooperating feed piston member, a hammer drill having a casing member connected to one of said feed members, a substantially radially disposed rotation handle carried by one of said members, a differential hammer piston in said casing of said hammer drill, said casing having a constant pressure chamber for a portion of said hammer piston, a chuck rotatably mounted on said casing of said hammer drill, a mechanically reversible motor carried by said hammer drill for rotating said chuck, conduit means supplying said motor with operating pressure fluid from said constant pressure chamber, a mechanically reversible reduction gearing carried by said hammer drill for operatively connecting said motor and chuck, and releasable means operative at will to prevent rotation of said chuck relative to said casing. 80
12. A rock drilling machine having, in combination, a casing, a hammer piston for operating a drill steel, a chuck rotatably mounted in said casing, said chuck formed for carrying said drill steel in such manner that when said chuck is rotated said drill steel must rotate with it, a fluid pressure operated motor and reduction gearing operatively connected to said chuck in such manner that when said motor is in operation said chuck will be rotated relative to said casing, and releasable means operative to lock said chuck directly to said casing to prevent relative rotation between them. 105
13. A rock drilling machine having, in combination, a casing, a hammer piston in said casing for operating a drill steel, drill steel supporting and rotating means rotatably mounted on said casing, fluid pressure operated motor and reduction gearing means carried by said casing for driving said drill steel supporting and rotating means, and locking means carried by said casing for releasably engaging said drill steel supporting and rotating means, said locking means operative independently of said motor and reduction gearing means to secure said support- 110
- ing and rotating means non-rotatably to said casing. 135
- In testimony whereof, I have signed my name to this specification.
